UNITED STATES PATENT OFFICE.

TALBOT G. MARTIN, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

AUTOMATIC COMMON-BATTERY TELEPHONE SYSTEM.

1,185,521.

Specification of Letters Patent.

Patented May 30, 1916.

Application filed May 2, 1905. Serial No. 258,508.

To all whom it may concern:

Be it known that I, TALBOT G. MARTIN, a citizen of the United States of America, and resident of Chicago, Cook county, Illinois, have invented a certain new and useful Improvement in Automatic Common-Battery Telephone Systems, of which the following is a specification.

My invention relates to automatic telephone systems of that particular character in which automatic switching machines are employed in place of the ordinary switchboard operators—that is to say, in which the connections at the central station or exchange are made automatically, through the medium of step-by-step switching machines, instead of through the medium of the switchboard operators ordinarily employed at manual board exchanges.

My invention relates more particularly to that type of automatic telephone systems in which the automatic switching machines are of two kinds, namely, "selectors" and "connectors," the "selectors" being adapted to respond to electrical impulses projected over the "line-circuits" by a calling subscriber, and each "selector" being adapted to perform an operation in accordance with an impulse or impulses representing one of the digits of the called number. As distinguished from this, a "connector" is adapted to respond to the impulses representing the last two digits of the called number, and to make the final connection directly with the line of the called subscriber. Ordinarily, and as hereinafter explained, a "selector" responds to the impulse or impulses representing one of the first digits of the called number, the vertical movement of its switch-shaft being under the direct control of the subscriber, so that the subscriber may pick out the desired group of trunk-lines running to other "selectors," or to "connectors," according to the size of the exchange. In a "selector," however, the rotary movement, after the switch-shaft has been actuated to the desired level, is automatic in this respect: that the swinging or movable switch-contacts continue to move around and traverse the stationary contacts until connection is established with an idle trunk-line, it being understood that after the calling subscriber has caused a "selector" to pick out the desired group of "second-selectors" or "connectors," as the case may be, the desired connection

is then established with the first trunk-line which is found idle, or with the first "connector" which is found idle; for the arrangement is such that the calling subscriber may use any one of a certain number 60 of "second-selectors," or of "connectors," as the case may be, for establishing a through connection to the line of the called subscriber. In other words, the subscriber may use any one of a certain number of trunk-line connections for making connection between his line and the line of the called subscriber; but when the "connector" is operated, it is then essential, of course, that both the vertical and rotary movements of the 70 switch-shaft thereof be under the direct control of the calling subscriber, so that the latter may not only cause the "connector" to pick out the particular group in which the called subscriber's line is included, but 75 may then also pick out the line running to the called subscriber's station.

As stated, the automatic telephone system to which my invention more especially relates is of that type in which the "selectors" 80 and "connectors" are operated on the step-by-step principle—that is, by means of ratchet mechanism adapted to give the switching contacts a step-by-step progressive movement in response to separate and distinct electrical impulses transmitted from the station of the calling subscriber.

Generally stated, the object of my invention is the provision of an improved, simplified and highly efficient telephone system 90 of the foregoing general character.

A special object is the provision of an improved construction and arrangement by which the current, both for talking and switching purposes, may be furnished from 95 a common battery or other centralized source of supply located at the exchange or central station.

Another object is the provision of a construction and arrangement whereby the current for talking purposes may be advantageously supplied to the talking circuit through certain switch-contacts of the "connector" employed in establishing the connection between the calling and called subscribers' lines.

A further object is to provide such a construction and arrangement of circuits and parts as will permit the switches to be released or restored over "relense-circuits" in- 110

cluding certain so-called "private-wipers" and "private-bank-contacts" of the said switches, and in a system in which the current for talking purposes is supplied, as stated, from a common battery through the "connectors" to the talking circuits established between different subscribers.

Another object is to provide means for establishing the flow of talking current in the calling line when the called subscriber answers.

It is also an object to provide certain details and features of improvement tending to simplify, improve and increase the efficiency and serviceability of an automatic common battery telephone system of this particular character.

To the foregoing and other useful ends, my invention consists in matters hereinafter set forth and claimed.

In the accompanying drawings, Figure 1 is a diagrammatic representation of circuits and switching mechanism employed when a subscriber at sub-station designated as No. 321 calls the subscriber at sub-station No. 220. To the left of the line X—X is represented that part of the switching apparatus known as a "first-selector," belonging to the calling subscriber. To the right of the line Y—Y is represented the same part belonging to a called subscriber, and between lines X—X and Y—Y that part of the switching apparatus known as a "connector." Fig. 2 is a diagrammatic representation of one of the unit parts of the switching apparatus known as a "first-selector-switch" together with bank-terminals 43^a and 47^a of trunking lines that lead to "connectors." Fig. 3 is a diagrammatic perspective representation of one of the unit parts of the switching apparatus known as a "connector-switch," together with bank-terminals 169^a and 173^a of trunk-lines that are connected with the subscribers' lines, which trunk-lines are known as "normal-trunks"; V^a and R^a representing a pair of so-called "line-normals," and 242^a a so-called "private-normal." Fig. 4 is a simplified diagram showing the method of distributing the talking-current from the common battery to the talking-circuit, and of charging the transmitters at the sub-stations.

Each sub-station is provided with the usual transmitter, induction-coil, ringer, receiver and switch-hook, together with a keyboard, push-button and other essential details of construction and arrangement for operating and controlling the switching apparatus or mechanism at the central station.

The "first-selector" may be of any suitable, known or approved construction (as represented in Fig. 2), and may comprise the usual "vertical" and "rotary" relays 13^a and 51^a; the bridge cut-off relay 385^a; the "rotary" and "vertical" magnets 82^a and 27^a,

together with the "release-magnet" 56^a, the "private-magnet" 59^a, and the "back-release-relay" 100^a. Other familiar features of a switch of this character are: a shaft having circular ratchet-teeth by means of which it is given a step-by-step longitudinal or endwise movement by the "vertical-magnet" 27^a; said shaft also having longitudinal ratchet-teeth by means of which it is given a step-by-step rotary movement by the "rotary-magnet" 82^a through the medium of any suitable, known or approved mechanical connections. On the said shaft are supported the so-called "line-wipers" or conducting-arms 44^a and 45^a, and the "private-wiper" or conducting-arm 42^a. This "first-selector-switch" is also further identified, it will be seen, by the circuit-changing-arms or wipers 73^a, 74^a, 21^a and 54^a mounted on a shaft 188^a which is attached to the arm 69^a, the whole comprising a so-called "side-switch" which is operated in the usual well known manner by a "private-magnet" 59^a, through the medium of any suitable or approved mechanism. The "connector-switch" operates on the step-by-step principle, like other switches, in a well known manner, and may be of any suitable, known or approved character; but in this case certain novel circuit arrangements and features of construction are provided, in addition to the elements or features usually found in a "connector-switch" of this character. For example: the said "connector" may comprise the usual "vertical" and "rotary" relays 109^a, 141^a; the "release-magnet" 311^a; the ringing-relay 254^a; and the "private-magnet" 146^a. Other familiar elements in a switch of this character consist of "vertical" and "rotary" magnets 119^a, 174^a—which are employed as in other switches—for imparting longitudinal and rotary step-by-step movements to the shaft 138^a on which are mounted the usual wipers 170^a, 171^a and 168^a.

The "connector" is further identified by the usual "side-switch" provided with switching-arms 128^a, 158^a, 159^a and 160^a, said "side-switch" being operated by the "private-magnet" 146^a. There are, however, certain novel elements or features included in the construction of said "connector". For example: the "differential-relay" 187^a by means of which a calling subscriber is enabled to restore his switching apparatus to its normal condition when a called subscriber fails to restore his receiver to its hook, and by means of which a called subscriber is enabled also to break the connection established with his line if the calling subscriber neglects to do so; also the so-called magnet-cut-off-relay 280^a used to control local internal circuits in the "connector", and a pole-changing relay 281^a by means of which the polarity of certain circuits are changed in order to provide the current nec-

essary for talking purposes. One of the principal features of novelty consists in the use of said "connector", in an improved manner, for supplying energizing current to the talking circuits of two connected subscribers.

The current for ringing bells or signaling is provided by apparatus of any suitable or approved type, indicated in Fig. 1 as a generator D, and may or may not make use of the common battery which provides current for talking and other purposes. Underneath the switches at central station are mounted banks 43^a and 47^a (Fig. 2), and 169^a and 173^a (Fig. 3) of a well-known or any suitable character.

Assuming that the switching apparatus or mechanism is in its normal condition, as shown in Figs. 2 and 3, and that subscriber at the left (Fig. 1)—which we have designated as No. 321—wishes to establish connection with the subscriber at the substation at the right—designated 220, his first act will be to remove the receiver 1 from switch-hook 2. This operation closes springs 3 and 4, springs 5 and 6, and springs 7 and 8. He now presses the push-button 9 two times in succession, disengaging spring 10 from contact with spring 11 twice, and making contact with spring 12 twice. This energizes the so-called "vertical-line-relay-coil" 13^a of "selector" S twice in succession through the following circuit: from the non-grounded pole of battery 14 over conductors 15, 352^a and 16^a, springs 17^a and 18^a, conductor 19^a, relay-coil 13^a, contact-point 20^a, switching-arm 21^a, conductor V, springs 10 and 12, conductors 22 and 300, springs 7 and 8, conductor 23 to ground G^a, to the grounded terminal G of battery 14. Referring to Fig. 2, the "vertical-line-relay" 13^a thus energized twice, actuates the armature 24^a twice, and closes contact between springs 25^a and 26^a twice, thus energizing "vertical-magnet" 27^a twice through the following circuit: non-grounded pole of battery 14, conductors 15, 57^a, 28^a and 29^a, "vertical-magnet" 27^a, conductor 30^a, springs 31^a and 32^a, springs 25^a and 26^a to ground G^a and to grounded terminal G of battery 14. This actuates the "vertical-armature" 34^a twice in succession, to which is fastened the arm 35^a having the L-shaped piece 36^a and pawl 37^a, the latter being subject to the tension of the spring 354^a. The first movement of armature 34^a, which is pivoted at points 356^a and 357^a, and which is always subject to the tension of the spring 353^a, disengages the so-called "release-link" 38^a from lug 329^a on the so-called double dog 39^a by means of the L-shaped piece 36^a. Said double dog is now left free to respond to the tension of the retracting spring 40^a, and its arms 354^a and 355^a are drawn against the circular and longitudinal

teeth 91^a and 92^a, respectively. At the same time that the "release-link" 38^a is disengaged from the double dog 39^a, the shaft 41^a is raised one step by pawl 37^a, the latter engaging with the circular teeth 91^a. As the shaft is raised, the arm 354^a of the double dog 39^a engages with said circular teeth and retains the shaft in its raised position. The next impulse raises the shaft 41^a another step in the same manner; the subscriber thus bringing the wiper 42^a opposite the first contact of the second row of so-called "private-bank-terminals" 43^a, and at the same time bringing wipers 44^a and 45^a, which are separated by insulating material 46^a, opposite the first contact of the second horizontal row of trunk-line-terminals 47^a.

Referring to Fig. 1, the next act of the operator consists in pressing the button 48 once, thus causing the spring 50 to break connection with the contact 49, and to make contact only once with spring 12. This momentarily energizes the "rotary-line-relay" 51^a of "selector" S through the following circuit: non-grounded pole of battery 14, conductors 15 and 16^a, springs 17^a, 18^a and 52^a, relay-winding 51^a, contact-point 53^a, switch-arm 54^a, conductor R, spring 50, spring 12, conductor 22, springs 7 and 8 to ground G^a, to grounded terminal G of battery 14.

Referring to Fig. 2, magnet 51^a, thus energized once, actuates the relay-armature 7^a once, thereby bringing springs 55^a and 26^a into contact once, and in turn actuating the "private-magnet" 59^a through the following circuit: non-grounded pole of battery 14, conductors 15, 57^a and 58^a, "private-magnet" 59^a, conductors 60^a and 61^a, springs 55^a and 26^a to ground G^a, to grounded pole G of battery 14. This actuates the "private-magnet-armature" 62^a once, to which is attached an arm 63^a having a saw-tooth escapement consisting of teeth 64^a, 65^a, 66^a and 67^a and an arm 68^a, and which swings on pivots 358^a and 359^a. As the "private-armature" 62^a is attracted, the arm 69^a—which constitutes part of the so-called "side-switch"—disengages from tooth 64^a under the tension of spring 70^a, and falls against tooth 65^a, but from which it in turn disengages when the armature 62^a returns to its normal position. Further movement of the arm 69^a is checked by reason of lug 71^a striking against a cam 72^a; and at this time the "side-switch-wipers" 73^a, 74^a, 21^a and 54^a have shifted from the first position, in contact with points 102^a, 103^a, 20^a and 53^a, to the second position and into contact with points 75^a, 76^a, 77^a and 78^a, respectively; and the "side-switch-wiper" 73^a, having now closed with the contact-point 75^a, causes the coils 79^a and 80^a of the "rotary-magnet" to be energized through the following circuit:

non-grounded terminal of battery 14, conductors 15, 57^a and 81^a, "rotary-magnet-coil" 79^a, springs 83^a and 84^a, "rotary-magnet-coil" 80^a, conductor 85^a, "side-switch-wiper" 73^a, contact 75^a to ground G², and to grounded terminal G of battery 14. The energized coils 79^a and 80^a actuate the "rotary-armature" 86^a—which is pivoted at points 360^a and 361^a—and on said armature 86^a is found the so-called "rotary-armature-finger" 88^a, interrupter-arm 87^a, and the arm 89^a on which is fastened the so-called "rotary-pawl" 90^a. When the "rotary-armature" 86^a is attracted by the magnet-coils 79^a and 80^a, the said "rotary-pawl" engages with the longitudinal teeth 92^a on the shaft 41^a, causing the latter to rotate one step. As the shaft is rotated, the arm 355^a of the double dog 39^a engages said longitudinal teeth, retaining the shaft in the advanced position. This brings "private-wiper" 42^a into engagement with the first contact of the second row of so-called "private-bank-terminals" 43^a, and the "line-wipers" 44^a and 45^a into engagement with the first contacts of the second row of "line-banks" 47^a. At the same time that pawl 90^a begins to rotate the shaft 41^a one step, as explained, the "rotary-armature-finger" 88^a begins to press the "private-armature" 62^a toward the pole-piece of "private-magnet" 59^a. As soon as the cam 72^a has rotated away from lug 71^a, the "side-switch-finger" 69^a falls against tooth 66^a on the arm of the "private-armature". By the time the wipers 42^a, 44^a and 45^a are moved to the first contacts of the second level of the bank-terminals, as was stated, and arm 69^a disengaged from the tooth 66^a, the interrupter-arm 87^a is drawn in far enough to break the circuit that energizes electro-magnets 79^a and 80^a, by separating springs 84^a and 83^a. This will allow the "rotary-armature" 86^a to return to its normal position, under the influence of a retracting spring 93^a, which, at the same time, allows the "private-magnet-armature" 62^a to regain its normal position. This allows the "side-switch-finger" 69^a to disengage with tooth 67^a, and to shift the "side-switch-wipers" 73^a, 74^a, 21^a and 54^a out of second position and into contact with points 94^a, 95^a, 96^a and 97^a, respectively; and this last position is known as the third position of the "side-switch".

55 The "side-switch-wipers" 21^a and 54^a having moved into contact with the points 96^a and 97^a, respectively, the subscribers' "line-conductors" V and R are thereby extended through said wipers and said contacts to conductors 99^a and 98^a to "line-wipers" 44^a and 45^a, and through the bank-conductors and over the selected trunk-line to some disengaged "connector", as will hereinafter more fully appear. At the same time, the "side-switch-wiper" 74^a, having engaged

with contact 95^a, a guarding potential is thereby established at the first contact of the second row or level of "private-bank" 43^a, by putting it in connection with the grounded terminal G of battery 14, as follows: 70 grounded terminal G of battery 14, ground G³ at "side-switch", contact 95^a, wiper-arm 74^a, conductor 99^a, so-called "back-release-relay" 100^a, conductor 101^a, "private-wiper" 42^a to first contact in second level of "private-bank" 42^a.

Referring to that stage of the call before subscriber #321 had pressed button 48, it will be seen that the shaft 41^a has been raised two steps, and that the shaft-wipers are each 80 opposite the first contact or terminal of the second level of their respective banks. It may be assumed that the first nine trunks or trunk-lines of the second level are in use by "first-selector-switches" similar to the one shown in Fig. 2. The switch using the first trunk in the second row will have its "private-wiper"—which is similar to "private-wiper" 42^a—in engagement with the first contact of the second row of a "private-bank" similar to the "private-bank" 43^a with which it is connected in multiple. Also, with this arrangement, the "side-switch" of said other "selector" is in the third position, and its wiper—similar to the "side-switch-wiper" 95^a 74^a—is in contact with a third contact similar to contact 95^a, thus bringing it into connection with the grounded terminal G of battery 14. The "private-wiper" of said other "selector" being connected with a 100 grounded "side-switch-wiper", as "private-wiper" 42^a, a guarding potential is established at the first contact of the second row or level of all "private-banks" similar to "private-bank" 43^a with which it is connected in multiple; and the same will be the case with the other eight busy trunks. Now, if subscriber No. 321, after having pressed button 48 once, he will then energize, as before, the "private-magnet" 59^a. This will again cause the "private-magnet" to attract its armature 62^a, disengaging "side-switch-finger" 69^a from tooth 64^a, and bringing it against tooth 65^a from which it also disengages when said armature 62^a resumes its normal position. Again, as before, the "side-switch-finger" 69^a will be found between teeth 66^a and 64^a and prevented from further forward advance, under the influence of retracting spring 70^a, by reason of the lug 71^a striking the cam 72^a.

The "side-switch-wipers" having shifted from first position to second position, and into electrical connection with contact-points 75^a, 76^a, 77^a and 78^a; and "side-switch-wiper" 73^a moving into contact with point 75^a, as before, will cause the energizing of coils 79^a and 80^a of "rotary-magnet". The "rotary-armature" 86^a will now be attracted 120

once, rotating shaft 41^a one notch, and engaging "private-wiper" 42^a with the first contact of the second row or level of bank 43^a, allowing "side-switch-arm" or finger 69^a 5 to fall against tooth 66^a. Owing to the guarding potential established by the other "selector" or "occupying-switch"—which we have supposed is using the trunk-line corresponding to the first contact or terminal 10 of the second level—as soon as "private-wiper" 42^a engages with said contact, and before the "rotary-armature" has started to return to normal position, the "private-magnet" 59^a is energized through the following 15 circuit: from the grounded terminal G of battery 14 through "occupying-switch" and circuit not shown, to first contact of second row of "private-bank" 43^a, to "private-wiper" 42^a, conductor 101^a, "back-release-return" 100^a, conductor 99^a, "side-switch-wiper" 20 74^a, contact-point 76^a, conductors 98^a and 60^a, "private-magnet" 59^a, conductors 58^a, 57^a, 15 to non-grounded pole of battery 14. Thus energized, the "private-magnet" 59^a 25 attracts its armature 62^a and relieves "rotary-armature-finger" 88^a of its guarding duty over the said armature—"side-switch-arm" 69^a disengaging with tooth 66^a and falling upon tooth 67^a; and shortly after the "rotary-pawl" 90^a has rotated shaft 41^a sufficiently to permit the double dog 39^a to engage with the first longitudinal or "rotary-tooth" 92^a, the interrupter-arm 87^a will then 30 be drawn forward sufficiently to separate springs 84^a and 83^a; thus breaking the circuit through "rotary-magnet-coils" 79^a and 80^a, and permitting the "rotary-armature" 86^a to fall back to its normal position, owing 35 to the tension of the spring 93^a. It will be noticed, however, that the "private-armature" 62^a is still held down by the circuit established through the "private-magnet" as a result of the guarding potential encountered at the "private-bank-contact". As soon 40 as the "rotary-armature" 86^a has returned to its normal position, springs 84^a and 83^a again make contact with each other, thus again energizing coils 79^a and 80^a of the "rotary-magnet" through the same circuit 45 as before; and this will again actuate "rotary-armature" 86^a and then cause "rotary-pawl" 90^a to engage with the longitudinal teeth 92^a, and to rotate shaft 41^a one step more, and to shift the "private-wiper" 42^a, 50 together with the "line-wipers" 44^a and 45^a, to the second contacts of the second level of their respective banks. As this second contact is also characterized, at this time, by a guarding potential, the "private-armature" 62^a will remain in its attracted position by reason of the circuit already described. As soon as the longitudinal teeth 92^a have been advanced far enough to allow 55 the double dog 39^a to engage with the second tooth, the interrupter-arm 87^a on the "ro- tary-armature" 86^a again breaks the circuit through the "rotary-magnet", and again falls back to its normal position. As soon as it does so, however, springs 83^a and 84^a 60 again come into contact with each other, causing the "rotary-armature" 86^a to rotate the shaft 41^a another step. This will be repeated as often as "private-wiper" 42^a continues to encounter "private-contact-points" in "private-bank" 43^a with an established 65 guarding potential. When the shaft 41^a has been rotated nine steps, the "private-wiper" 42^a will then engage the ninth contact of the second row or level, which also has a guarding potential. The "rotary-magnet" will 70 be energized once more, and shaft 41^a will be rotated one more step, moving "private-wiper" 42^a onto the tenth contact—which latter has no guarding potential—as it is not busy. As soon as the "private-wiper" 42^a leaves the ninth contact, the circuit through the "private-magnet" 59^a is broken and the "private-armature" 62^a is restored 75 to the charge of the "rotary-armature-finger" 88^a. As soon as the circuit through the "rotary-magnet" is again broken by arm 87^a, the "rotary-armature" 86^a then falls back again for the last time, allowing "private-armature" 62^a to resume its normal position. The "side-switch-arm" 69^a will then 80 disengage from tooth 67^a and fall against stop 189^a, shifting all the "side-switch-wipers" 73^a, 74^a, 21^a and 54^a to third position, and thus extending the calling subscriber's "line-conductors" V and R—as before—to a 85 "connector" not in use, through the "line-wipers" 44^a and 45^a, and over trunk-line-conductors 115^a and 143^a, as clearly indicated in Fig. 1.

Referring to Fig. 2, again it will be observed that the "side-switch-wiper" 74^a, being in the third position, is in contact with point 95^a, thus establishing a guarding potential at the tenth contact of the second row or level of the "private-bank" 43^a through 90 a circuit already described. It will also be seen that while "private-wiper" 42^a was passing over the contacts having a guarding potential, the "private-magnet" 59^a was energized through relay-coil 100^a; but this latter coil is of such low resistance as not to interfere with the working of coil 59^a; and at the same time coil 59^a is of such comparatively high resistance that the current passing through coil 100^a, when they are both in 95 series, is of such small strength that the magnetic force generated is not sufficient to draw down its armature 322^a against the tension of spring 320^a. The subscriber having thus extended his line to the proper "connector" (see Fig. 1), he will now press the button 9 twice in succession. This will again separate spring 10 from spring 11 twice, and also twice bring it into contact with the spring 12. This energizes the 100

"vertical-line relay coil" 109° twice in succession through the following circuit: non-grounded terminal of battery 14, conductors 15, 110° and 111°, springs 112° and 113°, 5 winding 114° of differential-coil 187°, "vertical-line-relay" 109°, conductor 115°, wiper 44°, conductor 99°, contact-point 96°, switching-arm 21°, conductor V, spring 10, spring 12, conductor 22, spring 7, spring 8, conductor 10 23 to ground G⁴, and through ground to grounded terminal G of battery 14.

Referring to Fig. 3, the energizing twice of the "vertical-relay-coil" 109° causes relay-armature 116° to be twice attracted, thus 15 twice closing contact between springs 117° and 118°; and this twice energizes the "vertical-magnet" 119° through the following circuit: non-grounded pole of battery 14, conductor 15, conductor 120°, springs 142° and 257°, spring 258°, conductor 123°, conductor 124°, conductor 125°, "vertical-magnet" 119°, conductor 126° contact-point 127°, switching-arm 128°, conductor 129°, spring 265°, spring 266°, conductor 132°, springs 25 117° and 118° to ground G⁵, and to grounded terminal G of battery 14. Thus energized, the "vertical-magnet" 119° actuates the "vertical-armature" 133° twice—being pivoted at points 105° and 106°—and provided with the arm 134°, the L-shaped piece 135°, and the so-called "vertical-pawl" 136°. The pawl 136°, under the tension of the retracting spring 362°, engages the teeth 137° and raises the shaft 138° one step. At the 30 same time, the L-shaped piece 135° disengages the double dog link 139° from the double dog 140°, thereby allowing the latter to drop into engagement with teeth 137° to prevent the shaft from falling back to its 35 original position while in operation. After the "vertical-armature" returns to its normal position, under the tension of the retracting spring 363°, a second impulse causes the pawl 136° to again engage with "circular 40 teeth" 137°, raising the shaft 138° one more notch or step, and thus bringing the "private-wiper" 168° opposite the first contact of the second row or level of "private-bank" 45 169°, and "line-wipers" 170° and 171°, which 50 are insulated from each other by suitable material 172°, opposite the first contact of the second row of "line-bank-terminals" 173°. It will be noticed that when the subscriber at sub-station No. 321 (Fig. 1) energized 55 "vertical-line-relay" 109°, by pressing button 9, the circuit was closed through winding 114° of differential coil 187°.

The differential-relay has two windings and is constructed in such a manner that its 60 armature 365° (Fig. 3) is only energized while current is passing through one of the windings, or when the coils are in multiple, but not when they are put in series by the act of the called subscriber in taking down 65 his receiver; so that the armature 365° will

be actuated in unison with the armature 116° of the "vertical-line-relay", but its actuation at this time has no significance or utility. In the next step, the subscriber No. 321 (Fig. 1) presses the button 48 once, 70 which disengages spring 50 from contact 49 once, and brings it into contact with spring 12 once; and this causes the "rotary-line-relay" 141° to be energized once through the following circuit: non-grounded terminal of battery 14, conductors 15, 110°, 111°, spring 142°, winding 143° of differential-relay 187°, "rotary-relay" 141°, conductor 314°, wiper 45°, conductor 98°, wiper 54°, conductor R, spring 50, spring 12, conductor 80 22, springs 7 and 8, conductor 23, and ground G⁴ to grounded terminal of battery 14; and this in turn energizes the "private-magnet" 146°, only once, through the following circuit: non-grounded terminal of battery 14, conductors 15, 110°, 111°, 256°, spring 142° and 257°, conductors 303° and 147°, "private-magnet" 146°, springs 145° and 118° to ground G⁵, to grounded terminal G of battery 14. 90

Referring to Fig. 3, thus energized the "private-magnet" 146° actuates the "private-armature" 150°. On this armature, which is pivoted on points 363° and 364°, are found the arm 151°, a ratchet or saw-tooth escape- 95 ment with teeth 152°, 153°, 154° and 155°, together with arm 156°. When the "private-armature" 150° is attracted, the "side-switch-arm" 157° disengages from the tooth 152° and comes in contact with the tooth 153°, 100 but from which latter it disengages when the "private-armature" 150° regains its normal position under the influence of the retracting-spring 108°. The "side-switch-wipers" 128°, 158°, 159° and 160° are, in this way, 105 moved from their first position in contact with points 127°, 161°, 162° and 163°, respectively, to what is known as the second position, and in contact with points 164°, 165°, 166° and 167°, respectively. 110

The next operation of subscriber #321 (Fig. 1) consists in pressing button 9 ten times; and this disengages spring 10 from spring 11 exactly ten times, and brings it into contact with the spring 12 ten times, 115 thus energizing the "vertical-line-relay" 109° ten times through the same circuit as before. In Fig. 3, the "vertical-line-relay" 109°, thus energized ten times, in turn actuates the relay-armature 116° ten times, thus 120 bringing together springs 117° and 118° ten times, and in turn energizing "rotary-magnet" 174° ten times through the following circuit: non-grounded terminal of battery 14, conductors 15 and 120, springs 142°, 257° 125 and 258°, conductors 123°, 124° and 175°, "rotary-magnet" 174°, conductor 176°, contact-point 164°, "side-switch-wiper" 128°, conductor 129°, springs 265° and 266°, conductors 132°, and springs 117° and 118°, 130

conductor 149° to ground G° and to grounded terminal G of battery 14. Thus actuated ten times, the so-called "rotary-magnet" 174° actuates the "rotary-armature" 178° ten times—which is kept under the tension of retracting spring 181°—and on which are mounted the arm 179° and a so-called "rotary-pawl" 180°, which latter is kept in its normal position by a retracting spring 182°. As in the case of the first "selector", each time that the "rotary-armature" 178° is attracted, the "rotary-pawl" 180° engages the teeth 183°, thereby rotating shaft 188° one step against the tension of spring 184°, but the shaft being held at each step by the arm 185° of the double dog 140°; for at this time, said arm engages the teeth 183°, and is held in such engagement by the tension of the retracting spring 180°. At the end of this operation, the "line-wipers" 170° and 171° will be found on the tenth contact of the second row or level of "line-bank-terminals" 173°, this particular contact or terminal being connected with the called subscriber's line, which latter is not busy; and "private-wiper" 168° will be found on the tenth contact of the second row or level of the "private-bank-terminals" 169°.

The next act of the subscriber No. 321 (Fig. 1) consists in again pressing the button 48 once, and thereby disengaging spring 50 from the contact 49, and closing it with the spring 12, and again actuating "rotary-line-relay" 141° in the usual manner. "Private-magnet" 146°, being thus energized but once, actuates the "private-armature" 150° but once, causing the "side-switch-arm" 157° to disengage from tooth 154° on its downward stroke, and from tooth 155° on its return to normal position, and falling against stop 191°, owing to the tension of retracting spring 190°. "Side-switch-wipers" 128°, 158°, 159° and 160° will, at this time, be drawn to the third position and into contact with points 194°, 195°, 196° and 197°, respectively. This final operation connects the calling subscriber with the subscriber called, through the so-called "normal-trunk-line-conductors" V° and R°, shown more clearly in Fig. 1, as follows: calling subscriber's "line-conductor" V, switching-arm 21°, contact-point 96°, conductor 99°, wiper 44°, conductors 115° and 198°, condenser 199°, conductors 200° and 201°, springs 202° and 203°, conductor 204°, switching-arm 159°, contact-point 196°, conductor 207°, wiper 170°, conductor V°, conductor V°, spring 208, contact 209, conductors 210 and 211, hook 212, spring 213, ringer 214, conductor 215, condenser 216, conductor 217, contact 218, spring 220, conductors R° and R°, wiper 171°, switching-arm 160°, conductor 222°, springs 223° and 224°, conductors 225° and 226°, condenser 227°, conductor 228°, wiper 45°, conductor 98°, contact-point 97°, wiper 54°, "line-con-

ductor" R, spring 50, contact 49, conductor 229, condenser 230, secondary winding 231 of induction-coil 236, conductor 232, receiver 1, conductors 233 and 234, springs 3 and 4, conductor 235, contact 11, spring 10 70 back to conductor V.

In Fig. 1, the shifting of the "side-switch-wiper" 158° into contact with point 195° establishes a guarding potential at the "private-contact" with which "private-wiper" 168° is now in contact, as well as at all other "private-contacts" connected with it; and this by reason of the fact that electrical connection has been established with the grounded terminal G of battery 14, through the following path: grounded terminal G of battery 14 to ground G° at the "side-switch", contact 195°, wiper 158°, conductor 238° to "private-wiper" 168° to "private-contact" which is in connection with the so-called "normal-trunk-conductor" 242°. At the same time that a guarding potential is established at the tenth contact of the second row or level of the "private-bank" 169°, a circuit is also established by way of said contact and along the "private-normal" 242° (as is clearly shown in Fig. 1), which energizes the so-called cut-off relay 239° of the called subscriber's "first-selector-switch", through the following circuit: non-grounded terminal of battery 14, conductor 15, magnet 239°, contact 240°, spring 241°, conductor 242°, wiper 168°, conductor 238°, switching-arm 158°, contact-point 195° to ground G° to grounded pole G of battery 14. Thus energized the cut-off relay-magnet 239° attracts the armature 243°, separating springs 244°, 245° and 246°, and thus cutting off the bridge formed by the "line-relays" 247° and 248° across the "line-conductors" V° and R°, and which is ordinarily closed through the following circuit: "line-conductor" V°, switching-arm 249°, "vertical-line-relay" 247°, springs 245° and 246°, "rotary-line-relay" 248°, switching-arm 250° to line R°. The object of opening this bridge is two-fold, and will again be referred to in the following description. The subscriber at sub-station #321 is now ready to ring the bell at sub-station #220, and he therefore presses the button 250, which causes spring 251 to break contact with spring 252 and close contact with spring 253; and this will cause the "vertical-line-relay" 109° to again be energized as follows: non-grounded terminal of battery 14, conductors 110° and 111°, springs 112° and 113°, winding 114° of differential-relay 187°, "vertical-line-relay" 109°, conductor 115°, wiper 44°, conductor 99°, contact 96°, switching-arm 21°, "line-conductor" V, spring 10, contact 11, conductor 235, springs 4 and 3, conductor 234, springs 5 and 6, springs 251 and 253, springs 7 and 8 to grounded terminal G°, and to ground G 130

of battery 14. The differential-relay is energized with the "vertical-relay", but is of no consequence or utility at this time. Thus energized, the "vertical-line-relay" 109° 5 will operate relay-armature 110°, which will close contact through springs 117° and 118°, and thus in turn energize the so-called "ringer-relay" 254°, through a circuit as follows: non-grounded terminal of battery 14, 10 conductors 15, 110°, 111°, 256°, springs 142°, 257°, 258°, conductors 259° and 260°, ringer-relay 254°, conductor 261°, contact-point 194°, switching-arm 128°, conductor 129°, springs 265° and 266°, springs 117° and 118° 15 to ground G° and to grounded terminal G of battery 14. Thus energized, the ringer-relay attracts the armature 303°, thereby separating spring 223° from 224°, and bringing it into contact with spring 207°, and at 20 the same time separating springs 203° from spring 202° and bringing it into contact with spring 268°. Springs 203° and 223° constitute terminals of sub-station No. 220, and springs 224° and 202° the terminals of 25 sub-station No. 321, while springs 267° and 268° constitute the terminals of the ringing machine D; and it is evident that the action of the ringer-relay 254° separates the line of sub-station No. 220 from the line of sub-station No. 321, and closes it with the terminals of the generator D, as long as subscriber No. 321 is pressing button 250. In this way, the ringer or signaling apparatus 214, of subscriber No. 220, is energized 30 through the following circuit: brush 269° of ringer-generator D, conductor 270°, springs 268° and 203°, conductor 204°, switching-arm 159°, contact-point 196°, conductor 207°, wiper 170°, conductors V° and V°, spring 208, contact 209, conductors 210 and 211, hook-switch 212, spring 213, ringer 214, conductor 215, condenser 216, conductor 217, contact 218, spring 220, conductors R° and R°, wiper 171°, conductor 221°, 40 switching-arm 160°, conductor 222°, springs 223° and 267°, conductor 271°, brush 272° lead back to ringer machine D. The bells 214 of station No. 220 will now ring until subscriber at sub-station No. 321 releases button 250, allowing relays 109° and 254° 45 to again resume their normal condition. Springs 203° and 223° falling back upon springs 202° and 224°, respectively, again establish connection between sub-station No. 321 and No. 220. Had not the cut-off-relay 239° opened the bridge across the "line conductors" V° and R°, the ringing current would also have passed through the bridging "vertical" and "rotary" "line-relays" 50 247° and 248°, energizing them and making it possible for the switch A to be operated, since if the armatures 386° and 387° are attracted the springs 388° and 389° are 55 grounded on the spring 107°, which would, as in switch S, result in actuating the ver-

tical and rotary magnets; and not only for this reason but also for the reason that it is desirable, as is well known, that during talking there be a minimum number of bridges across the talking line. 7

When the subscriber at sub-station #220 answers by removing his receiver 273 from the hook 212, the ringer-circuit will be opened at the junction of switch-hook 212 with spring 213, and the following springs 7 will close: 274 with 275, 276 with 277, and 278 with 279. Talking current will now be admitted on the line of sub-station #220, through its transmitter 284 and the primary-winding 282 of induction-coil 283, which 8 current also energizes the magnet-cut-off-relay 280° and the pole-changing-relay 281° of "connector" C, through the following circuit: non-grounded terminal of battery 14, conductors 15 and 110°, pole-changing-relay 281°, conductor 225°, springs 224° and 223°, conductor 222°, switching-arm 160°, contact-point 197°, conductor 221°, wiper 171°, conductors R° and R°, spring 220, contact 218, conductor 217, primary-winding 9° 282 of induction-coil 283, transmitter 284, contact-point 285, spring 286 to springs 276 and 277, conductor 287, springs 278 and 279, conductor 210, contact 209 to spring 208, conductors V° and V°, wiper 170°, conductor 207°, contact 196°, switching-arm 159°, conductor 204°, springs 203° and 202°, conductor 201°, magnet-cut-off-relay 280°, contact 288°, armature 287°, switching-arm 158°, contact 195°, ground G° to grounded terminal G of 10 battery 14. The battery current for talking purposes is furnished from the common battery 14 to transmitter 284 and primary-coil 282 of induction-coil 283, through magnet-cut-off-relay 280° and pole-changing-relay 10 281°, as previously stated, which, being energized, attract their respective armatures. Armature 289° of magnet-cut-off-relay 280°, being attracted, causes contact between springs 258°, 257° and 142° to be broken, thus 11 disconnecting the operating magnets of the "connector-switch" C from battery 14, so that they will not be actuated when the armatures of the "line-relays" 109° and 141° are energized. At the same time that armature 289° is attracted by its magnet 280°, armature 290° is attracted by the pole-changing-relay 281°, causing spring 113° to break away from spring 112°, and to come 12 into contact with spring 291°. As soon as this occurs, talking current is furnished to the line of sub-station #321 through the following circuit: non-grounded terminal of battery 14, conductors 15, 110°, 111° and 256°, winding 143° of differential-relay 187°, "rotary-line-relay" 141°, conductor 314°, wiper 45°, conductor 98°, contact 97°, switching arm 54°, "line-conductor" R, spring 50, contact 40, conductor 220, primary-winding 291 of 125 induction-coil 236, transmitter 292, contact 130

252, spring 251 to springs 6 and 5, conductor 234, springs 3 and 4, conductor 235, contact 11, spring 10, "line-conductor" V, switching-arm 21°, contact 96°, conductor 99°, wiper 44°, 5 conductor 115°, "vertical-line-relay" 109°, winding 114° of differential-relay 187°, springs 113° and 291° to ground G', and to grounded pole of battery 14. When this circuit is established, battery current passes 10 through both windings of differential-relay 187°, which are so wound that in this case one coil neutralizes the other, leaving the armature 365° (Fig. 3) in its normal position. It will be seen that the current is 15 furnished through "line-relays" 141° and 109°, energizing them, their armatures 144° and 116°, respectively, being attracted; but as all the operating coils which are connected with springs 117° and 145°, which 20 are under the control of said armatures, were disconnected from the non-grounded pole of the battery by the movement of the cut-off relay-armature 289°, the energizing of these "line-relays" has no effect upon existing conditions. Current along the same 25 path reaches transmitter 292 and primary-winding 291 of induction-coil 236, and the two subscribers are now ready to talk to each other.

30 When the subscriber at #220 speaks into transmitter 284, the resistance of the circuit in which it is included with the primary-winding 282 of induction-coil 283 is varied, causing the intensity of the current flowing to vary in unison. In this way, currents are induced in the secondary winding of induction-coil 293 at sub-station #220, in the usual way, which reach receiver 1 of subscriber's station #321 through the following circuit: secondary winding 293 of induction-coil 283, conductor 294, receiver 273, conductor 295, conductor 287 to springs 278 and 279, conductor 210, contact 209 to spring 208, conductors V¹ and Vⁿ, wiper 170°, conductor 207°, contact-point 196°, switching-arm 159°, conductor 204°, springs 203° and 202° to conductors 201° and 200°, condenser 199° conductors 198° and 115°, wiper 44°, conductor 99°, contact 96°, switching-arm 21°, "line-conductor" V, spring 10 to contact-point 11 to conductor 235, springs 4 and 3, conductor 234, conductor 233, receiver 1, conductor 232, secondary winding 231 of induction-coil 236, condenser 230, 55 contact-point 49, spring 50, "line-conductor" R, switching-arm 54°, contact-point 97°, conductor 98°, wiper 45°, condenser 227°, conductors 226° and 225° to springs 224° and 223°, conductor 222°, switching-arm 160°, 60 contact-point 197°, conductor 221°, wiper 171°, conductors Rⁿ and R, spring 220, contact-point 218, conductor 217 to condenser 216, to secondary winding 293 of the induction-coil. It will thus be seen that variations originating in the transmitter 284 of

sub-station #220 reach receiver 1 at sub-station #321 through an unimpeded path including the condensers 199° and 227°. In like manner, variations produced in transmitter 292 at sub-station #321 reach the receiver 273 at sub-station #220. When one subscriber has established connection with another, the instruments may be released in different ways. The called subscriber may not have answered, in which case the calling subscriber releases by restoring his receiver; the called subscriber having answered, the calling subscriber may release by hanging up his receiver first; the called subscriber may attempt to make a call before the calling subscriber has released; and last of all, the called subscriber may hang up his receiver before the calling subscriber.

We will now suppose that sub-station #321 has called sub-station #220 without receiving an answer, and that subscriber at station #321 hangs up his receiver on switch-hook 2; then finger 296 on switch-hook 2 will engage with spring 297, pressing it onto spring 298, and 298 onto 299, bringing the three into contact at one and the same time. These springs are known as "release-springs"; and the result of pressing the said springs into contact is that the "rotary-line-relay" is first energized from ground G⁴ through springs 8 and 7, conductor 300, conductor 301, springs 298 and 297, conductor 302, contact-point 49, spring 50 to line R, and, as before, through "rotary-line-relay" 141° to the non-grounded pole of battery 14, thus again actuating the armature 144° of this relay. By the attraction of armature 144°, springs 118° and 145° will in turn be brought together, causing "private-magnet" 146° to become energized through the same circuit already traced; the "private-magnet" thus energized in turn attracts its armature 150°, causing springs 265° and 266° to break contact, thus breaking 110 connection with ringer-relay 254°, and closing contact between springs 306° and 307°. Immediately after this takes effect, "vertical-line-relay" 109° becomes energized at the instant that the three "release-springs" 297, 115 298 and 299 come in contact with each other, as already explained, through the following circuit: ground G⁴ at sub-station #321, conductor 23, springs 8 and 7, conductors 300 and 301, springs 298 and 299, conductor 120 308, contact 11, spring 10 to "vertical-conductor" V through "vertical-line-relay" 109°, as before, to non-grounded terminal of battery 14. Thus energized, said coil attracts its armature 116°, as before, bringing 125 springs 309° and 810° into contact, and energizing the so-called "release-magnet" 311° of "connect" C, and the so-called "back-release-relay" 100° of "selector" S, through 130 the following circuit: non-grounded termi-

nal of battery 14, conductors 110°, 111° and 256°, springs 142° and 257°, conductor 303°, "release-magnet" 311°, conductor 312°, springs 309°, 310°, conductor 313°, wiper 42°, 5 conductor 101°, "back-release-relay" 100°, switching-arm 74°, contact 95° to ground G°, to grounded terminal G of battery 14.

The energizing of "release-magnet" 311° (Fig. 3) actuates the "release-armature" 10 315°, which strikes the double dog 140°, causing it to rotate about the pivots 340° and 341°, and throwing lug 316° under slot 317°, which latter is in the "release-link" 139°. The link 139° then drops over lug 316°; 15 and as double dog 140° is kicked in by "release armature" 315°, arm 334° on said double dog 140° in turn drives the link 335°, which is fastened by a pivot 336° to the arm 337° on the "side-switch-arm" 157°; the link 335° 20 being driven in, as just explained, causes "side-switch-arm" 157° to rotate about the pivots 338° and 339°, restoring "side-switch-wipers" 128°, 158°, 159° and 160° to their first positions, and causing "side-switch-arm" 25 157° to be restored to its normal position behind tooth 152°. Shaft 138°, thus left subject to the action of spring 184°, rotates back on rest 192° until arm 318° strikes pin 319°. At this juncture, rest 192° enters slot 320° 30 again, and shaft 138°, by its own weight, drops to its original position. At the same time that this occurs, "back-release-relay" 100° (Fig. 1), which is energized with "release-magnet" 311°, attracts its armature 322°, 35 moving springs 320° and 321° into contact. In this way, "release-magnet" 56° of the "selector" S becomes energized through the following circuit: non-grounded terminal of battery 14, conductor 15, conductor 323°, 40 "release-magnet" 56°, conductor 324°, conductor 325°, springs 320° and 321°, ground G° to grounded terminal G of battery 14.

Referring to Fig. 2, the "release-magnet" 56° attracts the "release-armature" 326° 45 against the pull of the retracting spring 327°. In this way, link 38° is brought forward, and slot 228° falls over lug 329°; and then when "release-springs" 297, 298 and 299 (Fig. 1), 50 at the subscriber's station, disengage from each other, retracting spring 327° draws the link 38° and double dog 39° back to their normal position. As the double dog 39° is drawn away from the circular and longitudinal teeth 91° and 92° by a rotary motion 55 about the pivots 348° and 349°, one of its arms 342° drives the link 343° along in the direction of its movement. Said link being pivoted on arm 344° by a pin 345°, and said arm 344° being a part of the "side-switch-arm" 69°, the result is that "side-switch-arm" 69° is rotated about the pivots 346° and 347°, 60 causing it to be restored to its normal position behind tooth 64°, returning "side-switch-wipers" 73°, 74°, 21° and 54° to their first 65 positions; and shaft 41°, being left subject to

the action of spring 330°, rotates back upon rest 193° until arm 371° strikes the post 332°. At this point the rest 193° engages the slot 333°, and shaft 41° drops of its own weight to its original position of rest, the whole 70 switch being completely restored. Subscriber at sub-station #220 having answered, it may be supposed now that the subscriber 75 #321 hangs up his receiver 1 on switch-hook 2 before subscriber #220 hangs up his receiver. It will be remembered that the magnet-cut-off-relay 280° and the pole-changing-relay 281° are in an energized condition, as well as "vertical-line-relay" 109° and "rotary-line-relay" 141°. Now, as subscriber 80 #321 hangs his receiver 1 on switch-hook 2, "release-springs" 297, 298 and 299 will be brought together, as before, with the result that "vertical-line-relay" 109° releases its armature 116°, owing to the fact that said 85 coil is short-circuited through the ground, for the time being, as follows: ground G° at sub-station #321, conductor 23, springs 8 and 7, conductors 300 and 301, springs 298 and 299, conductor 308, contact 11, spring 10, 90 "line-conductor" V, switching-arm 21°, contact-point 96°, conductor 99°, arm 44°, conductor 115°, "vertical-line-relay" 109°, winding 114° of differential-coil 187°, springs 113° and 291° to ground G°. 95

"Rotary-line-relay" 141° retains its energized condition by circuit established as follows: non-grounded terminal of battery 14, conductors 110°, 111° and 256°, winding 143° of differential-coil 187°, "rotary-line-relay" 141°, conductor 314°, wiper 45°, conductor 98°, contact-point 97°, switching-arm 54°, "line-conductor" R, spring 50, contact-point 49, conductor 302, springs 297, 298, conductors 301, 300, springs 7 and 8, to 100 grounded terminal G of battery 14. Under such conditions, it will be seen that current passes through only winding 143° of differential-coil 187°, which separates spring 287° from contact 288°. It will be remembered that this spring 287° forms part of the circuit for energizing magnet-cut-off-relay 280° and pole-changing-relay 281°. As soon as this current is stopped, the armature 289° of magnet-cut-off-relay 280° resumes 105 its normal position, with the result that the springs 142°, 257° and 258° are again brought into contact with each other, restoring the operating parts of the "connector" C to their normal positions. As soon as this takes place, the "private-magnet" 146° becomes energized through the usual 110 following circuit: non-grounded terminal of battery 14, conductors 110°, 111° and 256°, springs 142° and 257°, conductors 303° and 147°, "private-magnet" 146°, springs 145° and 118° to ground G°. Thus actuated, the "private-magnet" 146° attracts its armature 150°, separating springs 265° and 266°, and disconnecting ringer-relay as before, so that 115 120 125 130

ringing current will not be uselessly projected to the called station. As soon as the differential-relay, by becoming energized, separates spring 287° from contact 288°, the 5 armature 290° of the pole-changing-relay 281° is restored to its normal position, causing spring 113° to break away from spring 291° and make contact with spring 112°. At the instant that this occurs, "vertical-line- 10 relay" 109° becomes energized, as before, because the three "release-springs" 297, 298 and 299 are still together. Thus armature 116° of "vertical-line-relay" 109°, and armature 144° of "rotary-line-relay" 141°, being 15 attracted, at once bring springs 310° and 309° into contact, thereby causing the "release-magnet" 311° of "connector" C and "back-release-relay" 100° of "selector" S to become energized, with the result, as before, 20 that all the switches are brought to their normal positions, the "back-release-relay" energizing the "release-magnet" of "selector" S.

Again, it may be supposed that the 25 subscriber at substation #220 (Fig. 1) desires to make a call before subscriber at substation #321 has restored his receiver, and that the number he wishes to call is 9. He will, therefore, begin by pressing button 350 nine times; and the only result will be that 30 every time spring 208 and contact 209 separate, magnet-cut-off-relay 280° and pole-changing-relay 281° will be momentarily de-energized, their respective armatures falling 35 back each time to their normal positions. The contact between springs 208 and 351 produces no result, for the only thing accomplished is the short-circuiting of coil 280° through ground as follows: ground G¹⁰ 40 at substation #220, springs 274, 275, conductors 352 and 353, springs 351 and 208, conductors V¹ and Vⁿ, wiper 170°, contact-point 196°, switching-arm 159°, conductor 204°, springs 203° and 202° conductor 201°, 45 magnet-cut-off-relay 280°, contact 288°, spring 287°, switching-arm 158° and to ground G°; but as soon as the button 382 is pressed, and contact between spring 220 and contact-point 218 is broken, the magnet-cut- 50 off-relay and the pole-changing-relay will again fall back to their normal positions. Now, as soon as springs 220 and 351 engage each other, the pole-changing-relay 281° will be momentarily energized through the following circuit: from ground G¹⁰, springs 274 and 275, conductors 352 and 353 to spring 351, "line-conductor" R¹ to the path already traced to the non-grounded pole of the battery 14, and again to ground at G. 55 Thus energized, relay 281° will attract the armature 290°, shifting spring 113° from spring 112° to spring 291°. A circuit will now be closed, as before, through winding 114° of differential-relay 187° through "vertical-line-relay" 109° to substation #321,

back to "rotary-line-relay" 141°, through the other winding of differential-relay 187° to the common battery. The "line-relays" 109° and 141°, being thus energized, will again bring springs 310° and 309° into contact, 70 thereby energizing the "release-magnet" 311° of "connector" C, and the "back-release-relay" 100° of "selector" S, which in turn energizes the "release-magnet" 56° of the "selector" S, restoring the switches to their 75 normal positions, as before.

If we now take a case where the called subscriber #220 hangs up his receiver first, the "release-springs" 397, 398 and 399 will be brought together by switch-hook 212, as 80 at sub-station #321, with the result that both "line-conductors" V¹ and R¹ will be momentarily grounded as follows: from ground G¹⁰ to springs 274 and 275, conductor 352 to ground-spring 398, to springs 399 and 397, 85 to springs 208 and 220 and to conductors V¹ and R¹ respectively. The grounding of conductor V¹ will result in the short-circuiting of magnet-cut-off-relay 280° through ground in the manner already explained, which, being de-magnetized, restores the internal circuits of "connector" C. The pole-changing-relay 281° retaining its energized state, the switches will be released just as in the case 90 previous to this, where the subscriber attempted to call before the calling subscriber had restored his receiver.

Returning to that stage in the calling of #220 where the subscriber at sub-station #321 pressed the button 9 twice, and the 100 button 48 once, the button 9 twice again, and the button 48 once, and for the last time the button 9 ten times—it only remains for button 48 to be pressed once to complete the 105 desired connection. The position of the switches, it will be remembered, was as follows: The "first-selector" S had cut-in or established connection with "connector" C, and "connector" C had been raised two steps, and had also moved around ten points 110 or steps, the "side-switch" being in second position. Suppose, now, that subscriber #220 is busy; there are two conditions under which this may occur: First when subscriber #220 has been called by some subscriber, and, second, when subscriber #220 is calling. Assume, first, that the subscriber #220 has been called. Referring to Fig. 3, if this 115 is the case, there is a "connector-switch" set on or connected with the line that leads to subscriber's station #220, the wipers of which are set on the tenth contact of the second row or level of the respective banks, and the "side-switch" of which is in the third position. Guarding potential will, 120 therefore, be found at the tenth contact of the second row or level of the "private-bank" 160°, through a circuit similar to the following: grounded terminal G of battery 14 to ground G° of "side-switch" 158°, con- 125 130

ductors 237^c and 238^c to "private-wiper" 168^c, to "busy-bank-contact." Now, if the subscriber at sub-station #321 pushes the button 48, (Fig. 1), the rotary line relay 141^c will be energized in the manner already described, which will in turn cause the "private-relay" 146^c to be energized through the circuit already described. The armature 150^c of the "private-relay" 146^c (Fig. 3) will be attracted as before, and arm 156^c will separate springs 265^c and 266^c and close springs 306^c and 307^c. In this way, the "release-magnet" 311^c will be energized through the following circuit: non-grounded terminal of battery 14, conductors 15 and 120^c, springs 142^c and 257^c, conductor 147^c, conductor 383^c, "release-magnet" 311^c, conductors 384^c and 385^c, springs 307^c and 306^c, conductor 368^c, contact-point 165^c, "side-switch-arm" 158^c, conductors 237^c and 238^c, "private-wiper" 168^c to tenth contact of the second row or level of the "private-bank" 169^c, which contact has a guarding potential supplied through some "occupying-switch" to ground (not shown) and to grounded terminal G of battery 14.

As soon as the "release-magnet" 311^c is energized, the "release-armature" 315^c will be operated as usual, and the "connector" C will be restored to its normal position. The subscriber at sub-station #321 (Fig. 1), thinking that he has established connection, will press the signal-button 250, with the result that the "vertical-line-relay" 109^c is energized as before; but instead of the ringer-relay 254^c being operated, the "vertical-magnet" 119^c is energized, owing to the fact that the "side-switch" is now in its first position, and the "side-switch-wiper" 128^c in contact with contact-point 127^c. This circuit has already been pointed out and explained. As soon, therefore, as the "vertical-magnet" 119^c is actuated, the shaft 138^c (Fig. 2) is raised from its normal position, and the arm 318^c on said shaft, being raised with it, will allow springs 370^c and 369^c to come into contact with each other. In this way, the receiver at sub-station #321 (Fig. 1) is brought into a circuit where current of any suitable nature is provided, this current usually causing a buzzing sound that will notify the subscriber that the party called is busy. This busy current may be produced in any suitable way. In Fig. 1 it is supplied by having a circuit-interrupter B inserted in the primary-circuit of a step-down induction-coil 371^b. The primary-circuit of this induction-coil is as follows: non-grounded terminal of battery 14, conductors 15 and 374^b, primary-winding 372^b of induction-coil 371^b, interrupter B to ground G¹¹ to grounded terminal G of battery 14. This interrupted current induces a similar current in the secondary winding 373^b of induction-coil 371^b, which reaches re-

ceiver 1 at sub-station #321 by the following circuit: secondary winding 373^b of induction-coil 371, conductor 368^c, contact 369^c, spring 370^c, conductor 386^c, switching-arm 160^c, conductor 222^c, springs 223^c and 224^c, conductors 225^c and 226^c, condenser 227^c, conductor 228^c, wiper 45^c, conductor 98^c, contact-point 97^c, switching-arm 54^c, "line-conductor" R, spring 50, contact-point 49, conductor 229, condenser 230, secondary winding 231 of induction-coil 236, conductor 232, receiver 1, conductor 233, springs 3 and 4, conductor 235, contact-point 11, spring 10, "line-conductor" V, switching-arm 21^c, contact-point 96^c, conductor 99^c, wiper 44^c, conductor 115^c, "vertical-line-relay" 109^c, winding 114^c of differential-relay 187^c, springs 113^c and 112^c, conductors 111^c and 110^c, 15 and 374^b, and back to the second winding 373^b of the induction-coil 371^b. The subscriber at sub-station #321 hearing the busy signal, will know that the number he has tried to call is busy, and will hang up his receiver—calling some other time.

When receiver 1 is restored to its hook 2, "release-springs" 297, 298 and 299 will be brought into momentary contact, in the usual way; "vertical" and "rotary" "line-relays" 109^c and 141^c will therefore become energized through circuits already traced, actuating the "release-magnet" 311^c of the "connector" C, and also the "back-release-relay" 100^c of the "selector" S, which will in turn actuate the "release-magnet" 56^c of the "selector" S, restoring all of the switches to their normal positions in the manner already described. Suppose, however, that subscriber #220 is busy calling some other subscriber. It will be remembered that when the subscriber at sub-station #321 (Fig. 1) established connection with the subscriber #220, the "private-wiper" 168^c of "connector" C established connection, also, over "private-normal-line" 242^a with the cut-off-relay 239^a through springs 240^a and 241^a. In this way, every "first-selector" is connected directly by way of a "private-normal-line", similar to 242^a, with a "private-contact" in the "connector-banks", corresponding to its number. It is plain, therefore, that if subscriber #220 (Fig. 1) has made a call, the arm 379^a, similar to arm 371^a, on shaft 41^a will disengage with spring 241^a, similar to spring 376^a (Fig. 2), allowing spring 241^a to come into contact with spring 380^a, similar to spring 378^a. The result is that a guarding potential is established at the "private-contact" corresponding to the #220 in the "connector-banks", by connecting "private-normal" 242^a to ground G¹² through springs 241^a and 380^a. When the subscriber #321 now tries to establish final connection, by pressing the button 48, the "rotary-line-relay" of "connector" C is actuated in the usual way, and in turn ac-

tuates the "private-relay" of said "connector", in the manner already shown.

As soon as the "private-armature" 150^e is attracted, springs 306^e and 307^e come into contact, and the "connector-switch" will be released as before, and the calling subscriber (Fig. 1), as soon as he presses the signaling button 250, will receive a busy signal in the manner already explained. He will then restore his receiver, again releasing all the switches and leaving them in readiness for further calling. It may be that some time a subscriber will begin to make a call, and, not completing it, restore his receiver before the "first-selector-switch" has cut-in or made a connection. For example: In Fig. 1, should the subscriber at sub-station #321 begin to make a call by pressing button 9 twice, the "vertical-line-relay" 13^e of "selector" S will be twice momentarily energized, in the manner previously explained, raising the shaft 41^e (Fig. 2) to the second level. Now, as receiver 1 is replaced on the hook 2, the "release-springs" 297, 298 and 299 will be momentarily brought into contact; the "vertical-line-relay" 13^e will be momentarily energized through the following circuit: non-grounded terminal of battery 14, conductors 15, 352 and 16^e, springs 17^e and 18^e, conductor 19^e, "vertical-line-relay" 13^e, contact-point 20^e, switching-arm 21^e, "vertical-line-conductor" V, spring 10, contact-point 11, conductor 308, springs 299 and 298, conductors 301 and 300, springs 7 and 8, conductor 23 to ground G⁴ to grounded terminal G of battery 14; and the "rotary-line-relay" 51^e will be momentarily energized through the following circuit: non-grounded terminal of battery 14, conductors 15, 352 and 16^e, springs 17^e and 18^e and 52^e, "rotary-line-relay" 51^e, contact-point 53^e, switching-arm 54^e, "rotary-line-conductor" R, spring 50, contact-point 49, conductor 302, springs 297 and 298, conductors 301 and 300, springs 7 and 8, conductor 23, ground G⁴ to grounded terminal G of battery 14. In this way, the armatures of the "rotary" and "vertical" "line-relays" 13^e and 51^e will be simultaneously attracted, armature 7^e bringing springs 55^e and 26^e into contact and thereby energizing "private-magnet" 59^e through the following circuit: non-grounded terminal of battery 14, conductor 15, "private-magnet" 59^e, springs 55^e and 26^e to ground G¹, and to the grounded terminal of the battery 14. "Private-magnet" 59^e, being thus energized, attracts the armature 62^e, causing spring 32^e to break contact with spring 31^e and close contact with spring 381^e; at the same time, armature 24^e of "vertical-line-relay" brings 25^e and 26^e into contact, energizing the "release-magnet" 56^e through the following circuit: non-grounded terminal of battery 14, con-

ductors 15 and 323^e, "release-magnet" 56^e, conductor 324^e, springs 381^e and 32^e, conductor 387^e, springs 25^e and 26^e to ground G¹ to grounded terminal G of battery 14. Thus energized, the "release-magnet" 56^e (Fig. 2) will restore the switch to its normal position, in the manner already described, leaving it in readiness for further calling.

From the foregoing, it will be seen that I provide an exceedingly simple and highly efficient common battery system in which the current for talking purposes is fed to the talking-circuit through the coils 109^e, 141^e, 114^e and 143^e, at one side of the condensers 199^e and 227^e, and through the coils 280^e and 281^e at the other side of said condensers. In this way, only relay-coils are utilized for feeding the talking-current to the talking-circuit completed between subscribers' stations—that is, each and every coil through which the battery current is fed to the "line-circuit" for talking purposes is provided with an armature, and with suitable relay-contacts, and is thus characterized by functions other than that of acting as a resistance for regulating or limiting the flow of battery current to the talking-circuit. Again, it will be seen that the battery current for talking purposes is fed to the "line-circuit" through the "line-relays" 95 of the "connector"—that is, at one side of the said condensers—and through the other relays 280^e and 281^e to the circuit at the other side of said condensers. With this arrangement, the two "line-relays" 109^e and 141^e, and also the relays 280^e and 281^e, remain energized during conversation between the two subscribers; but at this time the differentially-wound relay 187^e is not energized, owing to the fact that its two windings are connected in series with the battery 14 and the transmitter 292 at the calling subscriber's station. Inasmuch as the connection between the non-grounded pole of the battery and the coil or winding 114^e includes the normally open switch-springs 291^e and 113^e of the pole-changing-relay 281^e, it is evident that the calling subscriber's transmitter receives no talking-current from the battery until said pole-changing-relay 281^e is energized, and the springs 291^e and 113^e thereby brought together, by the act of the called subscriber in removing his receiver from its switch-hook, in the manner already explained. The connection between the grounded pole of the battery and the magnet-cut-off-relay 280^e includes the "private-side-switch-wiper" 158^e, and also the switch-springs 288^e and 287^e of the differentially-wound relay 187^e.

It will be seen that the various coils—in this case all relay-coils—through which the battery current is fed to the talking-circuit, serve also as impedance for preventing the voice-currents from leaving the 130

6 talking-circuit between any two subscribers' stations and passing through the battery. In other words, the said battery is in bridge across the talking-circuit formed between 5 any two subscribers' stations, and the relay-coils are included in this bridge, and are also adapted to serve as impedance for preventing the shunting of voice-currents through the battery.

10 It will be readily understood that the different coils employed in the system can be of any suitable or desired resistance, according to the conditions of any particular case; but with respect to the "connector" I find 15 that good results can be obtained by making the coils 109°, 141°, 280° and 281° of 500 ohms resistance each, and by making the coils 114° and 143° of 75 ohms resistance each. The 20 voltage of the battery can be regulated, according to requirements, and in accordance with the character of the exchange and the transmitters employed at the subscribers' stations. In any event, however, the said relay-coils preferably have three functions, 25 to-wit: the energizing of their cores for the purpose of opening and closing circuits; the retardation of any voice-currents tending to stray from the talking-circuits; and the admission to the talking-circuits of the requisite 30 amount of current required for charging the transmitters at the subscribers' stations.

The relay 187° may be energized at various times during the operation of connecting 35 up one subscriber with another; but it is only usefully energized at one time—that is, when the calling subscriber hangs up his receiver and thereby releases the "connector-switch", and consequently the "selector" or 40 "selectors", employed, in the manner explained.

The magnet-cut-off-relay 280° is only energized for one useful purpose, and this is when the called subscriber takes down his 45 receiver and thereby completes a metallic circuit running to both sub-stations—one from the battery to the calling subscriber's station, and one from the battery to the called subscriber's station; and at this time 50 the two "line-relays" 109° and 141° being energized, and the springs 309° and 310° being closed together, and the energizing circuit of the "release-magnet" 311° being thus closed at the springs of the "line-relays", it 55 becomes necessary to open a switch-point in the "release-circuit" in order to prevent the "connector" from releasing. Consequently, the magnet-cut-off-relay 280° opens a switch-point in the circuit of the "release-magnet" 60 311° as soon as it is energized, and also opens a switch-point in the energizing circuit of the "private-magnet" 146°, which latter would be energized by the closing together of the springs 118° and 145° were it not for 65 some provision to the contrary. In this

way, the calling subscriber releases by simply energizing the differential-relay 187°, in the manner explained, and thereby deenergizing the magnet-cut-off-relay 280°. When this relay 280° is deenergized, it closes 7 the switch-points in the circuits of the "release-magnet" and "private-magnet", which are open during conversation between the two subscribers. The "release-magnet" 311° being, at such time, connected in series with 7 the "back-release-relay" 100° of the "selector", the closure of its circuit in this way effects a release not only of the "connector", but also of the "selector"; and it is obvious that this method of release, over a "release-circuit" including the "private-bank-contacts", may be applied to any number of "selectors"—that is, any number which may be found necessary in establishing connection between the calling subscriber's line and a 8: "connector."

The so-called pole-changing-relay 281° is adapted to be energized for two useful purposes, namely,—the shifting of the "vertical-line-relay" 109° from the non-grounded pole 90 to the grounded pole of the battery, and the releasing of the "connector" by the called subscriber. For example: If the calling subscriber does not release, the called subscriber can then release, in the manner explained, 95 by opening his circuit and immediately thereafter closing a grounded circuit through the relay 281°, so as to energize the two "line-relays"; and the relay 280° being necessarily deenergized at this time, it follows that the "release-magnet" and the "private-magnet" are energized in the manner previously described. In this way, either subscriber can release the switches. The called subscriber may release by simply 10: hanging up his receiver; but regardless of this, and as previously explained, the called subscriber is sure to release the "connector" and other switches if he attempts to make a call before the calling subscriber has hung up his receiver. 110

The relay 280° may be called a magnet-cut-off-relay, inasmuch as it is used for severing the connection between the magnets of the switch and the non-grounded pole of the 115 battery, it being observed that the circuits for the "vertical" and "rotary" magnets, and also the "release" and "private" magnets, of the "connector" extend in parallel from the non-grounded pole of the battery through their respective coils and thence over different paths—which are normally open—to the grounded pole of the battery. 120

The relay 281° may be termed a pole-changing-relay, inasmuch as it is used for 125 severing the connection by which the two "line-relays" 109° and 141° are normally bridged across the trunk-line and in addition for shifting the "vertical-line-relay" 109° from one pole of the battery to the 130

other, in the manner explained. When the calling subscriber releases the "connector" the act of replacing his receiver on the switch-hook short-circuits the "vertical-line-relay" 109^c and the differential-winding 114^c, thereby opening up the called subscriber's metallic "line-circuit", and deenergizing all of the coils included in such metallic "line-circuit". This, of course, results in the 10 shifting of the "vertical-line-relay" 109^c from the grounded to the non-grounded pole of the battery, and in the consequent and immediate inclusion of these two "line-relays" in a grounded circuit in parallel with each 15 other, thus closing the circuits through the "release-magnet" and the "private-magnet", in the manner explained. When the called subscriber releases, it will be seen that he does so through the medium of only the non-differentially-wound electro-magnetic means 20 in the "connector", the differentially-wound means remaining deenergized. As distinguished from this, however, the calling subscriber can effect a release or restoration of 25 the "connector" by and through the medium of the differentially-wound-relay—that is, when the calling subscriber releases, he does so through the medium of the differentially-wound relay. Obviously, the energizing of 30 the "private-magnet" of the "connector", when the calling subscriber releases, prevents a ringing of the called subscriber's bell.

I obtain increased efficiency and simplicity 35 of construction by using both of the "line-relays" of the "connector" for supplying talking-current to the talking-circuit established between subscribers' stations.

The "selector" herein shown and described 40 may be of the general type shown and described in Patent No. 815,321, granted March 13, 1906, to Keith, Erickson & Erickson.

The "connector" herein shown and described may be of the general type shown 45 and described in Patent No. 815,176, granted March 13, 1906, to Keith, Erickson & Erickson.

With a view to insuring a positive or 50 guarding potential at the "private-bank-contacts" of the "selector", in case a third subscriber should attempt to cut-in on the circuit just at the time one of the subscribers is releasing the switches, the "release-magnet" of the "connector" may be of 60 ohms 55 resistance and the "release-relay" of the "selector" of one-half ohm resistance. In this way, it is possible to release over a circuit including the "private-wiper" and "private-bank-contacts" of the "selector" without neutralizing the guarding potential established 60 at the "private-bank-contact"—that is, the contact which is in use—by reason of the connection existing at that time between such contact and the grounded pole of the 65 battery. In other words, the resistance be-

tween the non-grounded pole of the battery and the "private-bank-contact" of the "selector" is preferably much greater than the resistance between the grounded pole of the battery and said contact. Consequently, 70 should another subscriber attempt to establish connection with the contacts of a "selector" corresponding to those already in use between two subscribers' lines—that is, should another subscriber start the operation of another "selector", the latter will not only refuse to make connection with the contacts corresponding to the trunk-line already in use for conversational purposes, but will even refuse to make connection with 80 such contacts after the subscribers have finished talking and during the time that the "release-circuit" is closed; for by using the coil of the "release-magnet" of the "connector" as a resistance, in the manner specified, the necessary flow of current will take place from the grounded pole of the battery, through the "private-wiper" of the "selector", through the "private-bank-contact" 85 thereof, and thence through the "private-wiper" and bank-contact of the other "selector", and with the result that the latter "selector" will continue its rotary motion even though the "release-circuit" between the "selector" and "connector" in use has been 90 closed. This feature is, it will be seen, employed in a telephone exchange system in which the current both for talking and switching purposes is supplied from the same common battery or centralized source 100 of supply which energizes the "release-magnet" and "release-relay" and establishes a guarding potential at all "private-bank-contacts" which are busy or already in use.

It will be seen that no talking current is 105 on the calling line before the called subscriber answers. The called subscriber, in answering automatically establishes the flow of such current in the calling line.

What I claim as my invention is:

1. An automatic common battery telephone system comprising a connector having switch contacts and line relay coils for controlling the operation of the switch, a common battery talking-circuit established 115 through the switch-contacts of the "connector" and receiving current for talking purposes supplied from the common battery through the "line-relay-coils" of said "connector," and means for trunking a calling 120 subscriber to the connector.

2. An automatic common battery telephone system comprising a connector having contacts and "vertical" and "rotary" line-relays, and talking-circuit established 125 through the contacts of the "connector" and receiving current for talking purposes from the common battery through the windings of the so-called "vertical" and "rotary" "line-relays" of said "connector."

3. An automatic common battery telephone system comprising subscribers' lines, automatic switches including "connectors," each "connector" being provided with the so-called "vertical" and "rotary" "line-relays," bridged across the talking circuit, and with connections whereby current for talking purposes is supplied from the common battery through the coils of said relays to a calling subscriber's line.
4. An automatic common battery telephone system comprising subscribers' lines, automatic switches and trunk-lines for connecting one subscriber's line with another, each trunk-line having a pair of "line relay coils" normally bridged between its sides, said switches having step-by-step devices controlled by each of said relays, and connections whereby the current for talking purposes is supplied from the common battery through the said relays to the "line-circuits."
5. An automatic common battery telephone system comprising subscribers' transmitters, subscribers' lines connecting the transmitters with automatic switching apparatus, said switching apparatus including "connectors" each provided with a pair of normally-bridged "line-relays," step-by-step devices controlled by each of said relays, together with connections whereby current for talking purposes is furnished from the common battery through the said relays to a subscriber's line and transmitter.
6. An automatic common battery telephone system comprising a "connector" provided with a pair of normally-bridged "line-relays," a differentially-wound relay having its windings connected in series in bridge between said "line-relays," means for opening said bridge at a point between said windings when the "connector" is in use, and for including the common battery in the bridge at a point between the said windings, for the purpose of furnishing talking-current to the "line-circuits."
7. An automatic common battery telephone system comprising a "connector" provided with a pair of normally-bridged "line-relays," the middle point of the bridge between the two relays being normally connected with the non-grounded pole of the common battery, means for shifting one of said relays from the non-grounded to the grounded pole of the battery when the called subscriber answers, means whereby the talking-current is supplied from the common battery through the coils of said relays to the calling subscriber's line.
8. An automatic common battery telephone system comprising a "connector" provided with a pair of "line-relays," a relay provided with suitable switch-contacts and adapted when deenergized to connect the two "line-relays" in parallel with one pole of the common battery, but adapted when energized to shift one of said "line-relays" into connection with the other pole of said battery, together with means under the control of a calling subscriber for operating said "line-relays," and means under the control of a called subscriber for operating said third relay.
9. An automatic common battery telephone system comprising two subscribers' lines suitably connected together for conversational purposes, the means for connecting the two lines including a condenser in each side of the circuit, and also the switch-contacts of a "connector," said "connector" being provided with electro-magnetically-actuated step-by-step devices, and with a pair of "line-relays" for controlling the operation of said step-by-step devices, the common battery being bridged across the talking-circuit at points each side of the said condensers, and the said "line-relays" constituting a medium of connection between the battery and that part of the talking-circuit included between the said condensers and the calling subscriber's station, whereby current for talking purposes is supplied from the common battery to the subscribers' lines.
10. An automatic common battery telephone system comprising a "connector" provided with suitable electro-magnetically-propelled switching means, and with a pair of "line-relays" adapted to be operated by a calling subscriber for controlling the operation of said switching means, together with a magnet-cut-off-relay and a pole-changing-relay adapted to be operated by a called subscriber for rendering the said switching means inoperative and shifting one of said "line-relays" from one pole of the battery to the other, and a differentially-wound relay adapted to be controlled by a calling subscriber and provided with means for controlling the operation of the said magnet-cut-off-relay, the coils of all of said relays constituting a medium of connection for supplying current from the common battery to a completed "line-circuit" for talking purposes.
11. An automatic common battery telephone system comprising a "connector" provided with electro-magnetically-operated switching means, and with a pair of "line-relays" for controlling said switching means, together with a magnet-cut-off-relay and a pole-changing-relay, the magnet-cut-off-relay being adapted when energized to render the said switching means inoperative, and the said pole-changing-relay being adapted when energized to shift one of said "line-relays" out of connection with one pole of the battery and into connection with the other pole of the battery.
12. An automatic common battery telephone system comprising a "connector" provided with a pair of normally-bridged "line-

relays," the middle point of the bridge being normally connected with the non-grounded pole of the common battery, together with automatic means for opening said bridge 5 and shifting one of said relays into connection with the grounded pole of the common battery when a called subscriber answers.

13. An automatic common battery telephone system comprising a "connector" provided with electro-magnetically-actuated step-by-step switching means, a pair of "line-relays" for controlling said switching means, a magnet-cut-off-relay for controlling the connections between one pole of the common battery and the electro-magnets for actuating the said switching means, a pole-changing-relay suitably connected and adapted for shifting the said "line-relays" from a parallel to a series connection with the common battery, and a differentially-wound relay adapted and connected for controlling the flow of current through the said magnet-cut-off-relay.

14. An automatic common battery telephone system comprising a "connector" provided with a pair of normally-bridged "line-relays," the middle point of the bridge between the two relays being normally connected with the non-grounded pole of the common battery, together with a pole-changing-relay adapted when energized to open said bridge and connect the said battery in series between the two relays.

15. An automatic common battery telephone system comprising calling and called subscribers' lines suitably connected for conversational purposes, the medium of connection including a condenser in each side of the circuit, and means for bridging the common battery across the talking-circuit at points each side of said condensers, said means including windings of a differential-relay, and a pair of "line-relays" for the calling end of the circuit, and including a magnet-cut-off-relay and a pole-changing-relay for the called end of the completed circuit.

16. An automatic common battery telephone system comprising a couple of subscribers' lines suitably connected for conversational purposes, a medium of connection between the two lines including a condenser in each side of the circuit, and means for bridging the common battery across the talking-circuit at points each side of said condensers, said means including a pole-changing-relay for the called end of the circuit, and the system comprising means operable by the called subscriber through the medium of said relay for effecting a disconnection between lines.

17. An automatic common battery metallic line telephone exchange system comprising a "connector" provided with a dif-

ferentially-wound relay controllable by a calling subscriber for effecting a disconnection between lines, and provided also with non-differentially-wound electro-magnetic means controllable by the called subscriber for effecting a disconnection between lines, 70 together with connections whereby the talking-current is supplied from the common battery through the coils of said relay and electro-magnetic means to any talking-circuit established by the said "connector." 75

18. An automatic common battery metallic line telephone exchange system comprising a "connector" provided with non-differentially-wound electro-magnetically-operated means controllable by the called subscriber for effecting a disconnection between lines, and serving as impedance-coils through which current is supplied from the common battery to any talking-circuit established by the "connector". 80

19. An automatic common battery telephone system comprising a "connector" provided with a "vertical-magnet" and a "private-magnet", and also with a "rotary-magnet", together with "vertical" and "rotary" "line-relays" for controlling the energizing of said magnets, and means whereby current for talking purposes is supplied from the common battery through the coils of said "line-relays" to the calling end of 95 any talking-circuit established by the "connector".

20. An automatic common battery telephone system comprising a "connector" provided with "vertical" and "rotary" 100 magnets, a "private-magnet" and a "release-magnet" all normally connected to battery, and having "vertical" and "rotary" "line-relays" for controlling the energizing of said magnets, together with a magnet-cut-off-relay for severing the connections between the magnets and the common battery, a pole-changing-relay for shifting the "vertical-line-relay" into connection with the grounded pole of the battery, and for opening the bridge in which the two "line-relays" are normally included across the talking-circuit, and a differentially-wound relay for controlling the energizing of the said magnet-cut-off-relay. 110

21. An automatic common battery metallic line telephone exchange system comprising a "connector" provided with "vertical" and "rotary" magnets, a "release-magnet" and a "private-magnet" all normally connected to battery, together with a magnet-cut-off-relay for severing the connection between the said magnets and the common battery when a talking-circuit is established through the "connector". 115

22. An automatic common battery telephone system comprising an automatic switching machine provided with a "release-

magnet" normally connected to battery for effecting a restoration of the mechanism after conversation is completed, and provided also with a magnet-cut-off-relay for severing the connection between the common battery and the said "release-magnet" when a talking-circuit is established through the said switching machine.

23. An automatic common battery telephone system comprising a step-by-step switching machine provided with a "private-magnet" normally connected to battery, a "side-switch" operated by said magnet, and a magnet-cut-off-relay adapted for severing the connection between the common battery and the said magnet when a talking-circuit is established through the said switching machine.

24. An automatic common battery telephone system comprising a step-by-step switching machine provided with a "vertical-magnet" normally connected to battery, switching-contacts operated by said magnet, and a magnet-cut-off-relay adapted when energized to sever the connection between the said magnet and the common battery when a talking-circuit is established through contacts of the said switching machine.

25. An automatic common battery telephone system comprising a step-by-step switching machine provided with a "rotary-magnet" normally connected to battery, switching-contacts operated by said magnet, and a magnet-cut-off-relay adapted when energized to sever the connection between the common battery and the said magnet upon the establishment of a talking-circuit through the contacts of said switching machine.

40 26. An automatic common battery telephone system comprising a switching machine provided with electro-magnetically-operated releasing mechanism normally connected to battery, and a magnet-cut-off-relay adapted when energized to sever the connection between the common battery and the electro-magnet of the releasing means upon the establishment of a talking-circuit through the switching-contacts of the said machine.

55 27. An automatic common battery telephone system comprising a switching machine provided with electro-magnetically-actuated step-by-step switching means normally connected to battery, and a magnet-cut-off-relay adapted when energized to sever the connection between the common battery and the electro-magnet of the said means upon the establishment of a talking-circuit through the contacts of the said machine.

60 28. An automatic common battery telephone system comprising a "connector" provided with a pair of normally bridged

"line-relays", and with a differentially-wound relay having its windings normally connected in series between the said "line-relays", a battery having one pole normally connected with the bridge at a point between the said differential windings, and automatic means for connecting the common battery in series between the said differential windings.

29. An automatic common battery telephone system comprising subscribers' lines connected through the medium of a plurality of automatic step-by-step switching machines whereof one is provided with a "release-relay", and another with a "release-magnet", and a "release-circuit" for said switches including said relay and magnet, together with connections whereby talking-current is furnished through one of said machines to the talking-circuit established between subscribers.

30. An automatic common battery telephone system comprising two subscribers' lines connected for conversational purposes, the medium of connection between the two lines including a "selector" and a "connector", the "selector" being provided with a multiple-contact connected through the medium of a "release-relay" with the grounded pole of the common battery, the "connector" being provided with a "release-magnet" having one terminal connected with the non-grounded pole of the common battery and the other terminal in open connection with the said multiple-contact of the "selector", the said "release-magnet" being of higher resistance than the said "release-relay", together with a "release-circuit" including said magnet and relay and battery, and means under the control of either subscriber for closing said "release-circuit", the two lines receiving current for talking purposes from the common battery through the "connector" during conversation between the two subscribers.

31. An automatic common battery telephone system comprising a calling telephone line, a called telephone line, means for connecting the two lines together, release mechanism, a trunk release circuit, a back-bridge-relay controlling said circuit, a line circuit for energizing said back-bridge-relay, a differential relay controlling said line circuit, means for furnishing current to said circuits, and means for short-circuiting or shunting one of the windings of said differential relay to energize the latter and thereby deenergize the back-bridge-relay.

32. An automatic common battery telephone system comprising a connector provided with releasing means, said means including a differentially wound relay having normally closed contacts, and the system

comprising means for short-circuiting or shunting one winding of said relay to thereby release or restore the said connector.

33. An automatic common battery telephone system comprising a connector provided with automatic means for establishing the desired connection, automatic means for releasing or opening such connection, said releasing means including a differential relay having a pair of windings normally connected in parallel and adapted to oppose or counteract each other when connected and energized in series, and the system including means by which the calling subscriber short-circuits or shunts one winding of said relay to thereby restore the said connector.

34. An automatic common battery telephone system comprising a connector provided with automatic means for establishing the desired connection, a trunk line extending to said connector, a trunk-release circuit, a relay having normally closed contacts controlling said circuit, an energizing circuit for said relay, a differential relay controlling said energizing circuit, and means for short-circuiting or shunting one winding of said differential relay to thereby deenergize said other relay and restore the said connector.

35. An automatic common battery telephone system comprising a connector provided with step-by-step operating mechanism, release mechanism, a differentially wound relay, means for normally connecting the windings of said relay in multiple to the same pole of the common battery, means for connecting the windings of said relay in series, a circuit controlled by said relay, and means for short-circuiting or shunting one winding of said relay to cause the same to open said circuit.

36. An automatic common battery telephone system comprising a temporarily established talking circuit, a condenser in each side of said circuit, a battery for furnishing talking and switching current to the said system, means including a pair of differential relay windings for bridging the battery across the circuit at one side of said condensers, means including a pair of relay coils for bridging the battery across the circuit at the other side of said condensers, a line circuit controlled by the said differential relay windings, and local circuits controlled by the said relay coils.

37. An automatic common battery telephone system comprising a temporarily established talking circuit, a condenser in each side of said circuit, a battery for furnishing talking and switching current to the system, means including a pair of differential relay windings for bridging the battery across the circuit at one side of said con-

densers, said windings normally connected 65 in multiple to the same pole of the common battery, suitable coils for bridging the battery across the circuit at the other side of said condensers, means for releasing or opening said circuit, and means for initiating 70 the release by short-circuiting or shunting one of said differential relay windings.

38. An automatic common battery telephone system comprising a temporarily established talking circuit, inductive devices 75 for inductively connecting together different portions of the circuit, a battery, suitable means for bridging the battery across the circuit at one side of said inductive devices, means including a pair of differential relay 80 windings for bridging the battery across the circuit at the other side of said inductive devices, said windings normally connected in multiple to the same pole of the common battery, release mechanism for use 85 in releasing or opening the said circuit, and means for initiating the release by short-circuiting or shunting one of said differential relay windings.

39. An automatic common battery telephone system comprising a temporarily established talking circuit, inductive devices in the circuit, a battery for furnishing talking and switching current to the system, means including a pair of differential relay 95 windings for bridging the battery across the circuit at one side of said inductive devices, said windings normally connected in multiple to the same pole of the common battery, means for releasing or opening the circuit, 100 and means for initiating the release by short-circuiting or shunting one of said differential relay windings.

40. An automatic common battery telephone system comprising a temporarily established talking circuit, a battery for furnishing talking and switching current to the system, a differentially wound relay, having its windings normally connected in multiple with the same pole of the battery, 110 means for balancing the relay during conversation, means for releasing or opening said circuit after conversation, and means for initiating the release by unbalancing said relay.

41. An automatic common battery telephone system comprising a temporarily established talking circuit, release mechanism for use in releasing or opening said circuit, a differential relay having its windings normally connected in multiple with the same pole of the battery, means for then changing the connections so that said windings are energized in series, and means by which the calling subscriber initiates the release by short-circuiting or shunting one of the windings of said relay.

42. An automatic common battery tele-

phone system comprising a temporarily established talking circuit, release mechanism for use in releasing or opening said circuit, a differential relay, having its windings normally connected in multiple with the same pole of the battery, means for then changing the connections so that said windings are energized in series, and means by which the calling subscriber initiates the release by short-circuiting or shunting one of the windings of said relay, together with a battery for furnishing talking current through the windings of said relay to the said circuit.

43. An automatic common battery telephone system comprising a temporarily established talking circuit, automatic means for releasing or opening said circuit, said means including a pair of differential relay windings normally connected in multiple, means for then changing the connections so that said windings are energized in series and means for initiating the release by short-circuiting or shunting one of said windings, said system also comprising means for supplying talking current through the said windings to the said circuit.

44. An automatic common battery telephone system comprising a subscriber's microphone transmitter, an automatic connector-switch provided with a differentially wound relay, the windings of said relay normally connected in multiple, means for then changing the connections so that said windings are energized in series, release mechanism, a centralized source of talking current, a line circuit for charging said transmitter, said circuit including the windings of said relay, and the system comprising means for initiating the release by momentarily short-circuiting or shunting one of said relay windings.

45. An automatic common battery telephone system comprising telephone lines, a battery having one pole grounded and the other pole normally connected with both sides of each line, automatic switching machinery provided with a pair of line relay coils for controlling the operations thereof, and means for closing connection for supplying talking current from the battery through the said line relay coils to the calling telephone line.

46. In a telephone system, an automatic switch having an electromagnet for releasing purposes, another automatic switch having an electromagnet for releasing purposes, means including a trunk line conductor for connecting the two electromagnets in series, a pair of electromagnets for closing the said trunk-release circuit through said electromagnets, and means for supplying talking current through the windings of said pair of electromagnets.

47. In a telephone system, an automatic

switch having an electromagnet for releasing purposes, another automatic switch having an electromagnet for releasing purposes, means including a trunk line conductor for connecting the two electromagnets in series, a pair of electromagnets for closing the said trunk-release circuit through said electromagnets, and means for supplying talking current through the windings of said pair of electromagnets, said pair of electromagnets controlled by the calling subscriber.

48. In a telephone system, an automatic switch provided with an electromagnet for releasing purposes, another automatic switch provided with an electromagnet for releasing purposes, means including a trunk line conductor for connecting said electromagnets in series, a relay controlling the said trunk-release circuit through said electromagnets, and means for supplying talking current through the winding of said relay, said relay controlled by the called subscriber.

49. In a telephone system, a talking circuit, a pair of relay coils, a source of talking current, and subscriber-controlled means for connecting said source of current in series between said relay coils and bridging the same across the talking circuit.

50. In a telephone system, a talking circuit, a pair of relay coils normally bridged across the circuit, a source of talking current, and subscriber-controlled means for inserting said source of current between the said relay coils.

51. In a telephone system, a talking circuit, a pair of relays bridged across the circuit and controlled by the called subscriber, a source of talking current, and means controlled by the called subscriber for inserting said source of current in the bridge between said relay coils.

52. In a telephone system, a talking circuit, a pair of relay coils bridged across the talking circuit and controlled by the calling subscriber, a source of talking current, and means controlled by the called subscriber for inserting said source of current in the bridge between said relay coils.

53. In a telephone system, a talking circuit, reactive connections in said circuit, a pair of relay coils bridged across the circuit at each side of said reactive connections, a source of talking current, and subscriber-controlled means for inserting said source of current in both bridges between said relay coils.

54. In a telephone system, a normally closed bridge across a talking circuit thereof, said bridge containing relay coils, and subscriber-controlled means for opening said bridge and introducing a centralized source of talking current in the bridge with said relay coils.

55. A telephone system comprising a calling line and a called line, a talking circuit including said lines, automatic switches for extending a connection from a calling to a called line, suitable means for furnishing current for talking purposes, a pair of line relay coils permanently connected to said circuit and responsive to the calling subscriber for both calling and releasing purposes, and devices responsive to the act of the called subscriber in answering for establishing the flow of said current in both lines. 65
56. A telephone system comprising a calling line and a called line, a talking circuit including said lines, automatic switches for extending a connection from a calling to a called line, suitable means for furnishing current for talking purposes, a pair of line relay coils permanently connected to said circuit and responsive to the calling subscriber for both calling and releasing purposes, and devices responsive to the act of the called subscriber in answering for establishing the flow of said current in the calling line. 70
57. A telephone system comprising a calling line and a called line, a talking circuit including said lines, automatic switches for extending a connection from a calling to a called line, suitable means for furnishing current for talking purposes, a pair of line relay coils permanently connected to said circuit and responsive to the calling subscriber for both calling and releasing purposes, and devices responsive to the act of the called subscriber in answering for establishing the flow of said current in both lines, said devices including a single-wound relay common to a plurality of lines at the central station of the called line. 75
58. A telephone system comprising a calling line and a called line, a talking circuit including said lines, automatic switches for extending a connection from a calling to a called line, suitable means for furnishing current for talking purposes, a pair of line relay coils permanently connected to said circuit and responsive to the calling subscriber for both calling and releasing purposes, and devices responsive to the act of the called subscriber in answering for establishing the flow of said current in the calling line, said devices including a single-wound relay common to a plurality of lines at the central station of the called line. 80
59. A telephone system comprising a calling line and a called line, a talking circuit including said lines, automatic switches for extending a connection from a calling to a called line, suitable means for furnishing current for talking purposes, a pair of line relay coils permanently connected to said circuit and responsive to the calling subscriber for both calling and releasing purposes, and devices responsive to the act of the called subscriber in answering for establishing the flow of said current in both lines, said devices including a single-wound relay common to a plurality of lines at the central station of the called line. 85
60. A telephone system comprising a calling line and a called line, a talking circuit including said lines, automatic switches for extending a connection from a calling to a called line, suitable means for furnishing current for talking purposes, a pair of line relay coils permanently connected to said circuit and responsive to the calling subscriber for both calling and releasing purposes, and devices responsive to the act of the called subscriber in answering for establishing the flow of said current in the calling line, said devices including a relay at the central station of the calling line. 90
61. In a telephone system, the combination of automatic means for trunking a calling line to a called line, including a connector having a pair of line relay coils responsive to the calling subscriber for calling purposes, suitable instrumentalities for furnishing talking current to the lines, and automatic means responsive to the called subscriber for establishing the flow of such current through the coils of said relays to the calling line. 95
62. In a telephone system, the combination of a talking circuit temporarily established between calling and called substations, releasing means at the exchange or central station, and substation devices for operating said releasing means, comprising means for first opening the talking circuit, means for then grounding one side of said circuit, and means for finally grounding both sides of said circuit, said releasing means requiring all three of said steps when the calling subscriber releases, but requiring only the first step when the called subscriber releases. 100
63. In a telephone system, a connector having one motion to select groups and another motion to find a called line in any selected group, said connector provided with a single pair of line relays for controlling all the operations thereof, and means controlled at the connector for supplying current for talking purposes through said relays. 110
64. In a telephone system, a connector having one motion to select groups and another motion to find the called line in any selected group, said connector provided with a single pair of line relays controlling all the operations thereof, means controlled at the connector for supplying current for signaling purposes, and means controlled at the connector for supplying current for talking purposes through said relays. 115
65. In a telephone system, a connector having one motion to select groups and another motion to find the called line in any selected group, said connector provided with a single pair of line relays controlling all the operations thereof, means controlled at the connector for supplying current for signaling purposes, and means controlled at the connector for supplying current for talking purposes through said relays. 120
66. In a telephone system, a connector having one motion to select groups and another motion to find the called line in any selected group, said connector provided with a single pair of line relays controlling all the operations thereof, means controlled at the connector for supplying current for signaling purposes, and means controlled at the connector for supplying current for talking purposes through said relays. 125

65. In a telephone system, a connector having one motion to select groups and another motion to find the called line in any selected group, said connector provided with 5 a single pair of line relays controlling all the operations thereof, means controlled at the connector for supplying current for signaling purposes, circuits controlled at the connector for releasing purposes, and

means controlled at the connector for supplying current for talking purposes through said relays.

Signed by me at Chicago, Cook county, Illinois, this 5th day of April, 1905.

TALBOT G. MARTIN.
